UNITED STATES PATENT OFFICE.

DAVID A. ANDERSON, OF CHICAGO, ILLINOIS.

FIREPROOF STAIR.

1,078,403.

Specification of Letters Patent.

Patented Nov. 11, 1913.

Application filed February 27, 1911. Serial No. 611,015.

To all whom it may concern:

Be it known that I, DAVID A. ANDERSON, a citizen of the United States, residing at Chicago, in the County of Cook and State of Illinois, have invented certain new and useful Improvements in Fireproof Stairs, of which the following is a specification.

My invention relates to improvements in fire-proof stairs, and has for its general object to provide an improved metal-and-concrete stair structure which will be strong, cheap, simple, light, and non-combustible.

In the drawings, wherein I have illustrated an embodiment of my invention, Figure 1 is a perspective view of a fragment of a stairway, having different treads in different stages of completion; Fig. 2 is a transverse section of a single step; and Fig. 3 is a transverse section of a step embodying my invention in slightly modified form.

In the drawings, 5 indicates a stringer, preferably of metal, affording horizontal step-carrying ledges, 6, preferably formed of angle irons, suitably secured to the

25 stringers as by bolts or rivets 7. 8-8 indicate sheet metal foundation members, each of which comprises, in part, a horizontally disposed tread foundation or bed-plate 9 at its end resting upon the ledges 6, and secured thereto by bolts 10. Each said plate 9 has its forward edge bent upward to form a nosing 11, and then inward to form a lip 11', and in some instances I prefer that the nosing shall have 35 a series of apertures 12 in its lip, through which the cement or other material of the tread may key to form an anti-slip nose.

The rear edge of the bed plate 9 is bent upwardly to form a rear wall 13, generally opposing the nosing 11, and as shown in Figs. 1 and 2, where a closed stairway is to be provided, this rear wall may be carried upward to form a riser 14, having its edge turned back to form a flange as at 45 15, to be secured by bolts 16 to the bed member next above, just back of its nosing, or as shown in Fig. 3, where an open stairway is to be provided without risers, the rear wall 13 may have its edge turned 50 forwardly in a lip, as at 14, at the same elevation as the inturned lip of the nosing.

To provide the tread proper of the stair, each member or bed plate is filled with concrete, cement, or like plastic material, indicated at 17, to the level of the nosing lip

11', but I prefer that the concrete body 17 shall be reinforced by metal reinforcing devices which also serve effectually to unite and brace the nosing wall 11 and the rear wall 13 of the foundation. Thus, specifically, I provide transverse brace bars 18, each provided with a foot 19 at its ends, and said feet, I secure as by rivets 20 respectively to the nosing wall 11 and the rear wall 13 of the foundation member. 60 These brace bars 18 serve also as rests and spacers for longitudinal reinforcing rods 22 and to this end preferably the upper edge of each brace 18 is notched as at 23, for the reception of the appropriate rods 22 65 which extend from end to end of the step. The arrangement preferred locates these rods 22 at about the vertical center of the plastic mass 17 forming the tread proper, and obviously the rods and transverse braces 70 serve to distribute throughout each step strains imposed upon any point of the tread structure, and to reinforce the plastic mass against cracking, disintegration, or displacement. Additionally, the transverse bracing 75 maintains the sheet metal foundation members against bending or lateral displacement of its vertical walls and tends to prevent bending or buckling of the horizontal web 9 of each said bed portion, by throwing a portion 80 of the strains upon the nosing and rear wall. Where the apertured nosing is employed as shown in Fig. 1, the plastic mass 17 fills the apertures as at 17', and is smoothed off flush with or slightly protruding from the metal to form an anti-slip 85 edge for the tread.

While I have herein described in some detail a particular embodiment of my invention, it will be apparent to those skilled in the art that many changes might be made in detail without departure from the spirit of the invention and within the scope of the appended claims.

What I claim is:

1. In a stair structure, the combination with a stringer providing horizontal ledges, sheet metal foundation members carried by said ledges providing in an integral structure a tread-bed, a nosing upturned from one edge of said tread-bed, a riser upturned from the opposite edge of said tread-bed, and a rearwardly extending flange turned back from the free edge of the riser; means, below the edge of the nosing and 100 105 110

above the level of the tread bed, secured to and connecting said nosing and riser for mutual strengthening and bracing effect upon said nosing and riser; means securing 5 the rearwardly turned flange of each tread member to the under side of the tread-bed portion of the member next above, and a body of plastic material constituting the tread proper and confined by the nosing and 10 riser and reinforced by the bracing means of the nosing and riser.

2. A stair structure comprising foundation members each providing a tread bed having a front nosing and a rear wall bent 15 upwardly therefrom, transverse bracing connections extending between and securely attached to said nosing and rear walls at points above the bends between the bed and the nosing and riser respectively, said nos- 20 ing and riser being provided at such points with means for such attachment, and a plastic tread body embedding said braces for partial support by said vertical nosing and riser.

25 3. In a stair, a step comprising a sheet metal foundation formed to provide a tread bed, a front nosing, and a rear wall opposing said nosing each bent upwardly from the respective edge of the tread bed, 30 transverse braces connecting said nosing and the rear wall to maintain them in vertical position by mutual support, longitudinal reinforcing means, and a plastic tread body between said vertically maintained 35 nosing and rear wall and embedding said braces and longitudinal reinforcing means to provide one of a plurality of interchangeable units for stair construction.

4. In a stair, a step comprising a sheet 40 metal foundation formed to provide a tread bed, a front nosing, and a rear wall opposing said nosing, transverse braces connecting said nosing and the rear wall for mutual strengthening of said vertical nosing 45 and wall, longitudinal reinforcing rods carried by the transverse braces and, through the agency of said braces, by said vertical walls and a plastic tread body bounded by said bed, nosing and riser and embedding 50 the said braces and rods for support jointly

by said bed and, through said rods and braces, by nosing and riser.

5. In a stair, the combination of a foun- 55 dation member providing a nosing at the front, a rear vertical wall, bracing means be- 60 tween the nosing and rear wall connected to the nosing below its free upper edge, said nosing being perforated along its upper edge, and a tread body of plastic material embedding said bracing means and filling 65 said perforations whereby the nosing is braced by the embedded bracing means be- 70 low its upper edge, and at its upper edge is intimately associated with the plastic ma- 75 terial which is reinforced by, and which em- 80 beds, said bracing means, to form a complete 85 interchangeable stair unit.

6. In a stair, the combination with step- 90 carrying ledges, of a plurality of step struc- 95 tures, each comprising, in a single-piece sheet-metal structure a horizontal bed plate resting upon said step-carrying ledges, a nosing bent vertically upward from the for- 70 ward edge of the bed plate, a riser bent ver- 75 tically upward from the rear edge of the bed plate, and a horizontal flange at the up- 80 per edge of the riser for connection to the under side of the bed plate of the step next above; a bracing structure extending be- 85 tween and secured to said nosing and riser whereby said vertical and horizontal por- 90 tions of the sheet metal foundation member are braced against displacement or buckling, and whereby each foundation structure and its bracing may be completely assembled be- 95 fore erection; a body of plastic material fill- 80 ing the space between said nosing and the opposite portion of the riser; and reinforce- 85 ing members lying centrally embedded in said plastic body and carried by said brac- 90 ing structure, whereby the strains imposed upon said plastic body are borne in part by the vertical nosing and riser portions of the metal step structure.

In testimony whereof I hereunto set my 95 hand in the presence of two witnesses.

DAVID A. ANDERSON.
